(57) **CLAIM**

The ornamental design for a camping lamp as shown and described.

DESCRIPTION

FIG. 1 is a front, bottom perspective view of a camping lamp showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a rear, top perspective view thereof;

FIG. 9 is a front perspective view thereof, showing the camping lamp in a folded state of use;

FIG. 10 is an enlarged detail view taken from portion 10 of FIG. 1;

FIG. 11 is an enlarged detail view taken from portion 11 of FIG. 5; and,

FIG. 12 is an enlarged detail view taken from portion 12 of FIG. 7.

The evenly-spaced broken lines in the drawings depict portions of the camping lamp that form no part of the claimed design. In FIGS. 1, 7, 5, and 10-12, the dash-dot-dash broken lines in the drawings indicate enlarged portions which form no part of the claimed design.
